United States Patent Office

Des. 221,985

Patented Sept. 21, 1971

221,985

TABLE LAMP

Donald R. Kracke, 5620 Whitecliff Drive,
Palos Verdes Peninsula, Calif. 90274

Filed July 27, 1970, Ser. No. 44,146

Term of patent 14 years

Int. Cl. D26—05

U.S. Cl. D48—20

Fig. 1

Fig. 2

Fig. 3

Fig. 4

FIG. 1 is a front perspective view of a table lamp, representing the sun, showing my new design;

FIG. 2 is a rear elevational view thereof;

FIG. 3 is an elevational view of the side not shown in FIG. 1;

FIG. 4 is a bottom plan view thereof.

I claim:

The ornamental design for a table lamp, substantially as shown.
